UNITED STATES PATENT OFFICE.

LEWIS W. TRACY, OF NEW YORK, N. Y., ASSIGNOR OF ONE-HALF TO JAMES E. GRANNISS, OF SAME PLACE.

MACHINE FOR COVERING INSULATED CONDUCTING-WIRE WITH LEAD.

SPECIFICATION forming part of Letters Patent No. 434,007, dated August 12, 1890.

Application filed May 28, 1890. Serial No. 353,467. (No model.)

To all whom it may concern:

Be it known that I, LEWIS W. TRACY, a citizen of the United States, residing at New York, in the State of New York, have invented certain new and useful Improvements 5 in Machines for Covering Insulated Electrical Conductors with Lead, of which the following is a specification.

The object of my invention is to produce 10 a cheap, efficient, and practical machine for covering insulated conductors and cables with a lead pipe or sheath, though of course the invention may be used also for the manufacture of lead pipe. I by preference dispense 15 with what is known as the "die-block" that is ordinarily interposed between the head of the press and the cylinder in which the molten lead is contained, and I locate the pipe-forming device in the base of the cylinder.

20 My improvements will be fully understood from the following specification.

In the accompanying drawings, Figure 1 is a vertical longitudinal section through an apparatus embodying my invention; Fig. 2, an 25 end elevation of the block in which the core-bar or core-bar holder is formed or mounted, showing also the plate or block on which it is seated; Fig. 3, a plan view of the same, and Fig. 4 a vertical section of a slightly-different construction.

A represents the head of the press, and B the lead-cylinder. Between the cylinder and the head of the press I by preference place a block C, and upon this block I mount the 35 core-bar holder D, though in some cases the part D may constitute the core-bar itself. Of course I might mount the core-bar holder D immediately upon the head A of the press.

The core-bar or core-bar holder D is formed 40 with a base d, which rests upon the block C, and may be seated in a dovetailed groove therein, as shown. One end of this core-bar holder is of conical form and tapering after the manner of an ordinary core-bar, while its opposite 45 enlarged end is turned or ground to exactly fit the circular wall of the lead-cylinder, and the base d is similarly ground or turned to exactly fit within the cylinder.

When the block C carrying the core-bar 50 holder is placed upon the head of the press and the cylinder placed in position, the core-

bar holder occupies the lower end of the cylinder in exact and proper relation to two transverse concentric openings B' B², formed in opposite walls of the cylinder. One of these 55 openings B' communicates with and forms a continuation of the bore of the core-bar holder, while within the other and opposite the end of the core-holder or core-bar is seated the die E. The die may be adjusted in its seat 60 in the wall of the cylinder by means of a screw-threaded follower E'.

If the part D constitutes the core-bar proper, all the conditions exist for the manufacture of pipe or the covering of a cable or conductor with lead. The insulated conductor is led in through the hollow core-bar and through the die E, and the press being operated, the lead sheath is formed around it as it emerges from the machine through the hollow follower B². By preference a sleeve F is passed through the opening B' in the wall of the cylinder, and screws into the core-bar holder, as shown both in Figs. 1 and 4, and when a core-bar G is seated within the holder 75 D the sleeve F serves as a follower, by means of which it may be adjusted.

The purpose of inserting the core-bar G, as shown in Fig. 1, is to reduce the diameter to adapt the machine for covering a smaller conductor. By removing the part G and employing a die E of proper size a larger conductor or cable may be covered, the part D serving as the core-bar proper; but in any event I always prefer to use the sleeve F, because in the event of a minute quantity of lead flowing through the joint between the rear of the part D and the wall of the cylinder it could not reach the insulated conductor or cable.

As shown in Fig. 4, instead of mounting the part D in a dovetailed groove in the block C, it may be seated thereupon and its accurate position assured by a dowel-pin H on the base d, entering a socket in the block C, and similarly the exact position of the cylinder B may be insured by means of dowel-pins b on the under face of the cylinder, which enter corresponding sockets in the block C.

I claim as my invention—

1. The combination, substantially as set forth, of the vertical cylinder, a horizontal

core-bar arranged within the lower end of the cylinder opposite concentric transverse openings in the walls of the cylinder, one of which communicates with the interior of the core-bar, and a die located in the opposite opening.

2. The combination, substantially as set forth, with the cylinder, of a core-bar or core-bar holder which accurately fits within the lower end of the cylinder, the transverse opening through the wall of the cylinder communicating with the interior of the core-bar holder, and a sleeve F passing through said opening and seated in the core-bar holder, an opposite concentric opening B² in the wall of the cylinder, and a die seated therein.

3. The combination of the head of the press A, the cylinder B, the interposed block C, the core-bar or core-bar holder D, seated upon

said block and fitting within the lower end of the cylinder, and transverse concentric passages in the walls of the cylinder, one of which communicates with the interior core-bar, and a die arranged in the other, substantially as set forth.

4. The combination of a lead-cylinder with a core-bar holder having a base d and a conical core-bar portion, the holder being adapted to fit accurately in the lower end of the cylinder, substantially as and for the purpose set forth.

In testimony whereof I have hereunto subscribed my name.

LEWIS W. TRACY.
